(57) **CLAIM**

The ornamental design for a control panel for motion furniture, as shown and described.

DESCRIPTION

FIG. 1 is a front perspective view of a control panel for motion furniture according to a first embodiment of our design;

FIG. 2 is a front planar view thereof;

FIG. 3 is a bottom view thereof;

FIG. 4 is a rear view thereof;

FIG. 5 is a top view thereof;

FIG. 6 is a right side view thereof;

FIG. 7 is a left side view thereof;

FIG. 8 is a front perspective view of a control panel for motion furniture according to a second embodiment of our design;

FIG. 9 is a front planar view thereof;

FIG. 10 is a bottom view thereof;

FIG. 11 is a rear view thereof;

FIG. 12 is a top view thereof;

FIG. 13 is a right side view thereof;

FIG. 14 is a left side view thereof;

FIG. 15 is a front perspective view of a control panel for motion furniture according to a third embodiment of our design;

FIG. 16 is a front planar view thereof;

FIG. 17 is a bottom view thereof;

FIG. 18 is a rear view thereof;

FIG. 19 is a top view thereof;

FIG. 20 is a right side view thereof;

FIG. 21 is a left side view thereof;

FIG. 22 is a front perspective view of a control panel for motion furniture according to a fourth embodiment of our design;

FIG. 23 is a front planar view thereof;

FIG. 24 is a bottom view thereof;

FIG. 25 is a rear view thereof;

FIG. 26 is a top view thereof;

(Continued)

FIG. 27 is a right side view thereof;
 FIG. 28 is a left side view thereof;
 FIG. 29 is a front perspective view of a control panel for motion furniture according to a fifth embodiment of our design;
 FIG. 30 is a front planar view thereof;
 FIG. 31 is a bottom view thereof;
 FIG. 32 is a rear view thereof;
 FIG. 33 is a top view thereof;
 FIG. 34 is a right side view thereof; and,
 FIG. 35 is a left side view thereof.
 The broken lines show features of the control panel that form no part of the claimed designs of FIGS. 1-35.
